Primary Examiner — Kimberly Barnes(74) *Attorney, Agent, or Firm* — Ross Brandborg(57) **CLAIM**

I claim the ornamental design for a helmet shock absorber, as shown and described.

DESCRIPTION

FIG. 1 is a front view of my design for a helmet shock absorber placed in the helmet;

FIG. 2 is a side view thereof;

FIG. 3 is a top view thereof;

FIG. 4 is a rear view thereof.

FIG. 5 is an enlarged side view of an individual shock absorber shown separately for clarity of illustration;

FIG. 6 is an enlarged perspective view thereof; and,

FIG. 7 is an enlarged cut-away side view thereof in place in the helmet.

Certain features of the helmet are presented in broken lines to show environment and form no part of the claimed design.
